CATALYTIC CRACKING OF HYDROCARBONS

Joseph D. Danforth, Riverside, Ill., assignor to
Universal Oil Products Company, Chicago, Ill.,
a corporation of Delaware

Application November 9, 1942, Serial No. 464,984

14 Claims. (Cl. 196—54)

This application is a continuation in part of my copending application Serial No. 412,715 filed September 29, 1941.

This invention relates to the treatment of hydrocarbons for the conversion thereof into lower boiling hydrocarbons suitable for use in motor fuel and particularly to the production of individually lower boiling hydrocarbons of a branched chain structure which can be used as a starting material in synthetic processes or directly as high antiknock constituents of motor fuel blends of gasoline boiling range. More specifically, the invention is concerned with improvements in a catalytic cracking process wherein a metallic halide catalyst of the Friedel-Crafts type is introduced into the reaction zone by a liquid carrying medium.

It has been recognized for some time that there is a distinct limitation both as to quality and yield of product obtainable from strictly thermal cracking processes aimed at the production of optimum yields of high antiknock value gasoline. Even though cracking plants have been developed which are more or less perfect mechanically and where individual fractions of hydrocarbon charges and intermediately insufficiently converted products are subjected individually to conditions of temperature and pressure best suited for effective conversion, it has been found that high antiknock value materials useful as gasoline boiling range motor fuels are difficult to obtain without sacrificing yields due to losses by the formation of fixed gases on one hand and production of heavy carbonaceous residual materials on the other. It has further been found that gasoline produced by thermal cracking contains a substantial quantity of unsaturated hydrocarbons which have a tendency to decrease the effectiveness of added antiknock compounds such as tetraethyl-lead. To overcome these limitations, many catalytic processes have been tried with varying degrees of success. Substantially saturated gasolines having comparatively high octane numbers have been produced by cracking high boiling hydrocarbon oils in the presence of metallic halide catalysts of the Friedel-Crafts type such as aluminum chloride. The major drawback to this operation has been the excessive catalyst consumption due primarily to the production of heavy hydrocarbon catalyst complexes by the reaction between the fragmental unsaturated hydrocarbons formed during the cracking operation and the catalyst material.

This invention is directed to an improved process for cracking high boiling hydrocarbons in the

presence of a metallic halide catalyst of the Friedel-Crafts type. The improvements are primarily a novel method of introducing the catalyst into the reaction zone and the presence of a diluent in the reaction mixture. In the process herein disclosed, the diluent is also utilized as a means for the introduction of the catalyst. One of the essential features of the improved operation is the conduction of the cracking reaction in the presence of a small amount of catalyst and the continuous addition of catalyst to the reaction zone, in a liquid hydrocarbon carrying medium. In the ordinary operation, the reaction is conducted in the presence of the bulk of the catalytic agent. As a result, a large portion of the catalyst is contaminated and consumed without being effectively used. In conducting the operation in the manner hereinafter more fully described only a small portion of the catalyst is contacted with the hydrocarbons to be cracked while the major portion is maintained in a separate catalyst supply tower through which the liquid hydrocarbon carrying medium is passed.

The presence of a liquid diluent in the reaction mixture reduces the concentration of the reactive hydrocarbon, decreases the time of said hydrocarbon within the reaction zone and eliminates to a considerable extent the further decomposition of the desired products and the formation of heavy hydrocarbon catalyst complexes. This diluent also has a washing effect and removes the sludge-like materials which tend to coat the catalyst thereby presenting an active catalyst surface for contact with the incoming hydrocarbon reactant. Under some conditions, the diluent may also undergo conversion. For example, if normal butane is used as a carrying medium under conditions of temperature and pressure at which the operation is conducted a substantial amount of isobutane is produced. Although the concentration of active catalysts within the reaction zone is continually being decreased by the formation of hydrocarbon catalyst complexes, this depletion is compensated by the introduction of fresh catalysts in solution with the liquid carrying medium thereby maintaining the active catalyst concentration within the reaction zone substantially constant throughout the entire operation. The amount of liquid hydrocarbon introduced into the reaction zone as a carrying medium is dependent upon the particular type of hydrocarbon used for this purpose, but will ordinarily be within the range of approximately 40 to 90% by volume of the hydrocarbon oil being cracked. By operating in this manner, the catalyst will be

more efficiently utilized and the amount of hydrocarbon oil converted per pound of catalyst consumed substantially increased. Under certain conditions of operation, it may be desirable to add hydrogen and/or hydrogen chloride in amounts not exceeding 10 mol % of the reaction mixture.

In one specific embodiment, the present invention comprises a process for converting relatively high boiling hydrocarbon oils into substantial yields of lower boiling hydrocarbons by subjecting said hydrocarbon oil in a substantially liquid phase to contact within a reaction zone with aluminum chloride introduced to said reaction zone by a liquid carrying medium.

By the process of this invention, a metallic halide catalyst of the Friedel-Crafts type and particularly aluminum chloride is introduced into the reaction zone by means of a liquid hydrocarbon carrying medium. This liquid hydrocarbon carrying medium may be normal or isobutane formed in the process or introduced from an outside source, relatively low boiling normally liquid paraffins or naphthenic hydrocarbons, boiling within the gasoline boiling range, for example the approximate range of from about 10 to about 350° F. at atmospheric pressure. The liquid carrying medium is passed through a chamber containing a metallic halide catalyst maintained at such a temperature and pressure that the desired amount of catalyst is carried therefrom by the carrying medium. The actual amount of catalyst removed from the catalyst chamber is dependent upon the solubility of the aluminum chloride or other metallic halide catalysts in the particular hydrocarbon chosen as a carrying medium. The solubility, of course, will be controlled primarily by the temperature at which the carrying medium is maintained. The catalyst carrying medium and the hydrocarbon oil to be cracked are introduced to a reaction zone wherein a substantial portion of the high boiling hydrocarbons are converted into gasoline boiling range hydrocarbons. Although the reaction chamber may be a large empty chamber providing sufficient reaction time to produce the desired conversion, it is preferably packed with any well known granular porous or non-porous packing material which has no harmful effect upon the activity of the metal halide cracking catalyst. The particular material employed in any given reaction is dependent upon the hydrocarbons being treated, the temperature and pressure employed, the amount of catalyst used and other factors.

The features and advantages of the present invention will be further evident from the consideration of the following description of a characteristic operation in connection with the attached drawing which shows diagrammatically in general side elevation one type of apparatus in which the process of the invention may be carried out. For simplification, such units as furnaces, condensers, reboilers, etc. not essential to the description of the invention, have been eliminated from the drawing.

Referring to the drawing, normal butane is introduced through line 1 containing valve 2 into pump 33 which discharges through line 34 containing valve 35 into catalyst tower 3 wherein the normal butane contacts a supply of a metallic halide catalyst of the Friedel-Crafts type, under conditions of temperature and pressure such that a solution of the catalyst and the hydrocarbon is formed, containing an amount of catalyst dis-

solved therein sufficient to promote the cracking of a hydrocarbon oil when introduced in a subsequent reaction zone. The particular temperature at which catalyst tower 3 is maintained is dependent upon the type of hydrocarbon being used as a carrying medium. With butane the temperature is ordinarily within the range of approximately 140 to about 250° F. and under a pressure sufficient to maintain the butane in a substantially liquid phase. With various other hydrocarbons, the temperature may be lowered to approximately 100° F. or raised to about 350° F. The catalyst disposed within tower 3 may comprise aluminum chloride, zirconium chloride, zinc chloride, iron chloride, or mixtures thereof. However, for purposes of simplification, the description of this drawing relates to the use of aluminum chloride as the catalyst agent.

The butane containing the desired amount of aluminum chloride leaves catalyst tower 3 through line 4 containing valve 5 and is introduced into reactor 6 wherein it is contacted with a hydrocarbon charging stock, comprising either a kerosene or gas oil fraction from the primary distillation of a crude oil, introduced through line 36 containing valve 37 into pump 38 which discharges through line 24 containing valve 25 into reactor 6. As previously pointed out, in the preferred mode of operation reactor 6 shall be a packed chamber containing any solid granular packing, either porous or non-porous which does not deleteriously affect the activity of the catalyst. The temperature within reactor 6 is ordinarily maintained within the range of approximately 200 to 750° F., but preferably within the range of 200 to about 500° F. This temperature will be controlled somewhat by the particular hydrocarbon chosen as the carrying medium, since one of the essential features of this invention is that a substantial portion of the carrying medium be dissolved within the hydrocarbon oil being cracked to act as a diluent. The pressure will be controlled by the temperature and the amount of carrying medium dissolved in the reaction products desired, but will ordinarily be within the range of 150 to 2000 pounds.

As shown in the drawing, the aluminum chloride containing stream and the hydrocarbon oil to be cracked are in parallel flow. However, this invention is not limited to any particular flow in the reaction zone. The aluminum chloride containing stream may also be introduced counter current to the gas oil stream and effective results obtained.

Although only one catalyst supply tower and one reaction tower are shown in the attached diagrammatic drawing, more than one may be employed simultaneously or intermittently either in parallel or series flow.

The reaction products leave reactor 6 through line 7 containing valve 8 and are introduced into fractionator 9 wherein the isobutane and normal butane charged to the process or formed during the operation in admixture with any light hydrocarbon gases formed are separated from the heavier hydrocarbons. The butane stream is withdrawn through line 10 containing valve 11 and is introduced into fractionator 12 wherein the isobutane and lighter hydrocarbons are separated from the normal butane and recovered through line 16 containing valve 17 as a product of the reaction. The normal butane is withdrawn from fractionator 12 through line 18 containing valve 19 and recycled through pump 30 which discharges through line 31 containing valve

32 into line 34. The excess normal butane formed during the reaction is withdrawn through line 39 containing valve 40 and recovered as a product of the reaction.

The hydrocarbons boiling higher than butane are withdrawn from fractionator 9 through line 13 containing valve 14 to fractionator 15 wherein the gasoline boiling range hydrocarbons formed during the reaction are separated from the insufficiently converted hydrocarbons. These gasoline boiling range hydrocarbons are withdrawn through line 20 containing valve 21, cooled and condensed, and recovered as a product of the reaction. The insufficiently converted hydrocarbons are withdrawn through line 22 containing valve 23 into the suction of pump 26 which recycles these hydrocarbons through line 27 containing valve 28 into reactor 6.

If it is desired to have hydrogen or hydrogen chloride present within reactor 6, they may be introduced either singly or together through line 41 containing valve 42 into line 4 which directs them in admixture with the butane catalyst solution into reactor 6.

The following examples are introduced to illustrate the improved results obtained from the process, although they are presented with no intention of limiting the scope of the invention in exact correspondence with the examples given, since some latitude is possible in the type of packing material used in the reaction zone, the amount of catalyst introduced to said zone, the conditions of operation, etc.

Example I

A butane fraction comprising essentially normal butane is heated to 200° F. under a pressure of 250 pounds per square inch and passed through a bed of granular aluminum chloride disposed within a catalyst supply tower. The effluent from the tower is commingled with a 31.0° A. P. I. kerosene fraction in a packed reaction zone maintained at 250° F. under a pressure of 500 pounds per square inch. A ratio of volumes of butane to the volumes of kerosene is maintained at about 1:1. A once through yield of 34% by volume of 400° F. endpoint gasoline of 78 octane number and 2 bromine number is obtained. The actual aluminum chloride consumption is approximately two pounds per barrel of kerosene charge. About 23 mol % of the normal butane charge is converted into isobutane.

Example II

For comparative purposes, the same kerosene charging stock is heated to 250° F. and introduced under 500 pounds per square inch pressure into a reaction zone containing granular aluminum chloride. A once through yield of 32% by volume of 400° F. endpoint gasoline with a 77.4 octane number is obtained. While the once through yield of gasoline is only slightly less than that obtained when operating in accordance with the improved method shown in Example I, the consumption of aluminum chloride is increased approximately two fold to about 4 pounds per barrel of charge.

I claim as my invention:

1. A process for producing lower boiling hydrocarbons from higher boiling hydrocarbons which comprises passing said higher boiling hydrocarbons through a reaction zone containing a solid packing material capable of retaining a deposit of metal halide catalyst, passing a separate stream of liquid hydrocarbons boiling with-

in the approximate range of 10 to 350° F. under atmospheric pressure in contact with a body of a metallic halide catalyst of the Friedel-Crafts type under conditions such as to dissolve catalyst therein, commingling the catalyst containing stream with the stream of higher boiling hydrocarbons within the reaction zone, and maintaining the reaction zone at a cracking temperature to therein convert a substantial portion of the hydrocarbons into lower boiling products.

5 2. A process for producing gasoline boiling range hydrocarbons from higher boiling hydrocarbons which comprises passing a stream of said higher boiling hydrocarbons through a reaction zone containing a solid packing material capable of retaining a deposit of an aluminum halide catalyst, passing a separate stream of a liquid hydrocarbon boiling within the approximate range of 10 to 350° F. under atmospheric pressure in contact with a body of aluminum halide catalyst under conditions such as to dissolve catalyst therein, commingling the resultant catalyst containing stream with a stream of the higher boiling hydrocarbons within the reaction zone, and maintaining the reaction zone at a cracking temperature to therein convert a substantial portion of the hydrocarbons into lower boiling products.

10 3. A process for producing gasoline boiling range hydrocarbons from higher boiling hydrocarbons which comprises passing a stream of said higher boiling hydrocarbons through a reaction zone containing a solid packing material capable of retaining a deposit of an aluminum halide catalyst, passing a separate stream of a liquid hydrocarbon boiling within the approximate range of 10 to 350° F. at atmospheric pressure in contact with a body of aluminum halide catalyst under conditions such as to dissolve catalyst therein, commingling the resultant catalyst containing stream with the higher boiling hydrocarbon stream in the presence of hydrogen halide within the reaction zone, maintaining the reaction zone at a cracking temperature to therein convert a substantial portion of the hydrocarbons into lower boiling products and separating the latter from the effluent of the reaction zone.

15 4. A process for producing lower boiling hydrocarbons from higher boiling hydrocarbons which comprises passing a stream of the heavier hydrocarbons through a reaction zone containing a solid packing material capable of retaining a deposit of aluminum halide catalysts, passing a separate stream of liquid butane in contact with a body of aluminum halide catalyst under conditions such as to dissolve therein aluminum halide from said body, commingling the resultant catalyst containing butane stream with the stream of higher boiling hydrocarbons in the presence of hydrogen halide within the reaction zone, maintaining said reaction zone at a cracking temperature to therein convert a substantial portion of the hydrocarbons to lower boiling products and separating the latter from the effluent of the reaction zone.

20 5. A conversion process which comprises introducing hydrocarbons into a reaction zone containing a body of solid packing material, supplying to said reaction zone a separate stream of liquid substantially saturated hydrocarbons containing a dissolved metal halide catalyst, and effecting conversion of a substantial portion of the hydrocarbons into lower boiling hydrocarbons in said zone in the presence of the catalyst introduced in said separate stream.

6. A conversion process which comprises introducing a stream of hydrocarbons into a reaction zone containing a body of solid packing material, subjecting a separate stream of liquid substantially saturated hydrocarbons to contact with a metal halide catalyst under conditions such that said separate stream dissolves at least a portion of the metal halide catalyst, introducing the resultant solution into said reaction zone, and effecting conversion of a substantial portion of the hydrocarbons into lower boiling hydrocarbons in said zone in the presence of the catalyst introduced in said separate stream.
7. The process of claim 6 further characterized in that said liquid hydrocarbons comprise liquid butane.
8. The process of claim 6 further characterized in that conversion of the hydrocarbons is accomplished in the presence of a hydrogen halide.
9. A conversion process which comprises introducing a stream of hydrocarbons into a reaction zone containing a body of solid packing material, subjecting a separate stream of liquid substantially saturated hydrocarbons to contact with an aluminum halide under conditions such that said separate stream dissolves at least a portion of the aluminum halide, introducing the resultant solution into said reaction zone, supplying a hydrogen halide to said zone and maintaining the reaction zone at cracking conditions to effect conversion of the hydrocarbons in the presence of the catalyst introduced in said separate stream.
10. The process of claim 9 further characterized in that said aluminum halide comprises aluminum chloride and said hydrogen halide comprises hydrogen chloride.
11. The process of claim 9 further characterized in that the cracking reaction is accomplished in the presence of hydrogen.
12. A cracking process which comprises introducing a hydrocarbon oil heavier than gasoline to a reaction zone containing a body of solid packing material and maintained at cracking temperature, simultaneously introducing to said zone a stream of paraffinic hydrocarbon liquid containing a dissolved aluminum halide catalyst, and cracking the oil in said zone in the presence of the catalyst introduced thereto in said paraffinic liquid.
13. The process as defined in claim 12 further characterized in that hydrogen is introduced to said zone during the cracking of the oil therein.
14. The process as defined in claim 12 further characterized in that said paraffinic liquid comprises a butane.
